MAGNET COIL

Ralph E. Ferris, Pittsburgh, and John R. Shirley, Saltsburg, Pa., assignors to Westinghouse Electric Corporation, East Pittsburgh, Pa., a corporation of Pennsylvania

Application July 20, 1945, Serial No. 606,064

2 Claims. (Cl. 175—21)

1

Our invention relates, generally, to magnet coils and, more particularly, to coils for electromagnetic relays and switches.

Sometimes a magnet coil which is designed to operate on a relatively low voltage is subjected to a relatively high voltage because of trouble in some other part of the control system in which the coil is utilized. The high voltage causes the coil to become so hot that it explodes or bursts into flame, thereby setting fire to surrounding apparatus. An external fuse in the coil circuit is not satisfactory for some applications because of the extra connections required for the fuse and the blowing of the fuse by temporary overcurrent conditions which are not dangerous to the coil itself.

An object of our invention is to prevent a magnet coil from becoming overheated when subjected to excessive voltage.

Another object of our invention is to protect a magnet coil against excessive voltage without requiring an external fuse in the coil circuit.

A further object of our invention is to provide a magnet coil in which a fusible portion constitutes part of the coil winding.

Other objects of our invention will be explained fully hereinafter or will be apparent to those skilled in the art.

In accordance with one embodiment of our invention, a relatively short length of wire of a smaller size than that utilized for the coil winding is encased in a fireproof sleeve and wound in as a part of a magnet coil. The reduced section of wire fuses open when the coil is subjected to a relatively high voltage, thereby protecting the remainder of the coil winding and preventing setting fire to surrounding apparatus.

For a fuller understanding of the nature and objects of our invention, reference may be had to the following detailed description, taken in conjunction with the accompanying drawing, in which:

Figure 1 is a view, in plan, of a magnet coil embodying our invention;

Fig. 2 is an enlarged view, in section, taken along the line II—II of Fig. 1;

Fig. 3 is an enlarged view of a portion of the coil winding, and

Fig. 4 is an enlarged detail view, showing the joint between the two wires of a different size.

Referring to the drawing, a magnet coil 10 shown therein comprises a plurality of turns of insulated wire 11 of a predetermined diameter and substantially one turn of wire 12 of a smaller diameter than the wire 11. One end of the

2

smaller wire 12 is connected to one end of the larger wire 11 and constitutes part of the coil winding.

As shown, the coil may be made by winding the wire 11 on a tube 13 in the usual manner. A layer of fireproof insulation 14, such as sheet mica, is then wound around the wire 11; the mica being of sufficient length to overlap the joint 15 between the smaller wire 12 and the larger wire 11.

10 As shown in Fig. 4, the joint 15 between the wires 11 and 12 may be formed bylapping the end of the wire 12 back on itself to form two strands, twisting the two wires together and then soldering the end of the wire 11 to part of the doubled-back portion of the wire 12. The smaller wire 12 may be encased by a sleeve 16 of flexible fireproof insulation, such as fiberglass, which extends over the joint 15 between the wires 11 and 12. As shown in Fig. 1, exposed ends of the wires 11 and 12 are available for connecting terminal leads in the usual manner.

As explained hereinbefore, the short length of wire 12 fuses open when an excessive voltage is applied to the coil, thereby protecting the remainder of the coil and preventing fires or explosions. If desired, the outside insulation may be removed from the coil and the length of small wire replaced, thereby making the coil again available for service at a relatively small expense.

30 Magnet coils of the present type may be utilized in electromagnetic relays and switches of various types. They are particularly suitable for use on the control apparatus utilized in street cars and trolley buses where the apparatus is mounted in a relatively small amount of space, and there is danger of a fire being started by the failure of one coil when it is subjected to an excessive voltage. The present structure has been found to be more satisfactory than attempting to 40 protect the apparatus by means of fuses, which will blow under temporary overload conditions not dangerous to the magnet coils. The blowing of fuses results in the stopping of the operation of the vehicle, thereby causing considerable inconvenience.

Since numerous changes may be made in the above described construction, and different embodiments of the invention may be made without departing from the spirit and scope thereof, 50 it is intended that all matter contained in the foregoing description or shown in the accompanying drawing shall be interpreted as illustrative and not in a limiting sense.

We claim as our invention:

55 1. A magnet coil comprising a plurality of turns

of wire of a predetermined diameter, a length of fusible wire made of the same material and being of a smaller diameter than the first-named wire, said smaller wire being disposed on the outside of the larger wire and connected to the larger wire to constitute part of the coil winding, one end of the smaller wire being lapped back on itself and twisted to one end of the larger wire to form a joint therebetween, and a layer of fireproof insulation disposed between the smaller and the larger wires and overlapping the joint between said wires.

2. A magnet coil comprising a plurality of turns of wire of a predetermined diameter, a length of fusible wire made of the same material and being of a smaller diameter than the first-named wire, said smaller wire being disposed on the outside of the larger wire and connected to the larger wire to constitute part of the coil winding, one end of the smaller wire being lapped back on itself and twisted to one end of the larger wire to form a joint therebetween, a layer of fireproof insulation disposed between the smaller and the

larger wires and overlapping the joint between said wires, and a sleeve of fireproof insulation enclosing said smaller wire.
